Primary Examiner—Cathron Brooks*Assistant Examiner*—Deanna Fluegeman(74) *Attorney, Agent, or Firm*—Whyte Hirschboeck Dudek S.C.(57) **CLAIM**

An ornamental design for a scissors, as shown and described in FIGS. 1-7.

DESCRIPTION

FIG. 1 is a perspective view of the design;

FIG. 2 is a side view of the embodiment shown in FIG. 1;

FIG. 3 is a top view of the embodiment shown in FIG. 2, rotated 90 degrees;

FIG. 4 is a side view of the embodiment shown in FIG. 2, rotated 180 degrees;

FIG. 5 is a bottom view of the embodiment shown in FIG. 2, rotated 90 degrees;

FIG. 6 is an end view of the embodiment shown in FIG. 2, rotated counter clockwise 90 degrees; and,

FIG. 7 is an end view of the embodiment shown in FIG. 2, rotated clockwise 90 degrees.

The broken lines shown in FIGS. 1-7 are for illustrative environmental purposes only and form no part of the claimed design.
